(57) **CLAIM**

The ornamental design for an inflatable dinosaur toy, as shown and described.

DESCRIPTION

FIG. 1 is a perspective view of an inflatable dinosaur toy showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The dash-dash broken lines in the drawings depict portions of the inflatable dinosaur toy that form no part of the claimed design. The dot-dash broken lines represent boundaries of the bottom inner most flat area of the feet of the inflatable dinosaur to and form no part of the claimed design.
